UNITED STATES PATENT OFFICE.

CHARLES E. LINEBARGER, OF CHICAGO, ILLINOIS.

BATTERY-TEMPERATURE CONTROLLER.

1,363,889.

Specification of Letters Patent. Patented Dec. 28, 1920.

Application filed March 17, 1919. Serial No. 283,186.

To all whom it may concern:

Be it known that I, CHARLES E. LINEBARGER, a citizen of the United States, residing at 4315 Kenmore avenue, Chicago, in the county of Cook and State of Illinois, have invented new and useful Improvements in Battery - Temperature Controllers, of which the following is a specification.

My invention relates to devices for regulating the temperature of storage batteries, means being provided whereby storage batteries may be kept near predetermined temperatures which are most advantageous for their efficient action.

The invention consists of a thermostatic device, the temperature of which is controlled by the temperature of a storage battery; the device being set to operate at a predetermined temperature and being connected with a lever which actuates one or more valves, one valve controlling a supply of heated air or gas and another, if desired, controlling a supply of air at lower temperature, all so arranged as to heat or cool, by means of the gases, the storage battery.

The accompanying drawings and the following description set forth one mechanical form embodying the invention; Figure 1 of the drawings being an elevation of the battery with the temperature controlling devices mounted thereon; and Fig. 2 being a plan view of all of the elements which comprise my invention.

The thermostatic device may be of any suitable form. I prefer an ordinary wafer thermostat 1, which may be fastened to the wooden side of the battery box 2; or, in order to get closer contact between the interior of the battery and the thermostat, a part of the wood may be cut away to provide an opening 3 so that the thermostat may fit snugly against the cells 4 of the battery, as indicated in the drawing. A tightly fitting cover 5, made of an acid-resisting material, and one that is a poor conductor of heat, is placed over the thermostat on the outside of the battery box. A contact point 6 is mounted on the thermostatic wafer. The strip 7 is screwed to the side of the battery box, and is bent and cut out so as to accommodate a pin 8 acting as a pivot for the lever 9. A spring 10 is fastened to the strip 7 by a screw passing through the spring into the wood of the box 2 and tends to force the end of the lever against the

point 6. The lever 9 is perforated for the passage of the pivot at the fulcrum 11. A set screw 12 is provided for adjusting the distance between the contact point 6 and one end of the lever 9. A set screw 13 in one end of the link 14, connects the lever 9, and the valve handles 15 and 16, through the tie-rod 17, connecting the two valve handles of the valves 18 and 19. A pipe 20, perforated with holes, passes part way around the battery box 2. The pipe 20 is joined to an air horn 22 by means of the pipe 23, for furnishing air at the atmospheric temperature, while the pipe 20 also is connected, by means of the pipe 24, to a supply of hot air or heated gases provided in any suitable manner. The hot air is preferably provided by means of a member 25 connected with the exhaust pipe 26 of an automobile. The valves 18 and 19 control the admission of the air or gases into the pipe 20, one of the valves opening as the other closes. Preferably a box 27 incloses the battery box 2, the pipe 20 and the thermostat and its mechanism.

When the temperature of the battery passes a predetermined point, the thermostat 1 causes the lever 9 to move in such a direction as to close the valve 19 leading to the supply of colder air, and to open the valve 18 controlling the supply of heated gases. The gases pass into the box 27, through the openings 21. The outside of the battery is thereby subjected to the action of the hot gases and a rise in temperature ensues. As soon as this reaches the predetermined point, the lever 9 is made, by the action of the thermostat, to move in the opposite direction, shutting off more or less of the hot gas and allowing a complementary amount of cool gas to enter through the valve 19. When a very material quantity of the exhaust gases from the engine is used to heat the battery, it may be passed through a pipe, not perforated with rows of holes as shown, but which encircles the battery container and discharges from the distal ends into the open air, the battery being heated mainly by the hot pipes; and a perforated sleeve or concentric pipe may be fitted around the exhaust pipe in order to protect the battery box from excessive temperatures.

I claim as my invention:

1. The combination of a storage battery,

- a pipe for supplying heated gas, a pipe for supplying cool air at substantially the temperature of the atmosphere, a container or box inclosing the storage battery, a valve in 5 each of said pipes, a tie-rod joining pivotally said valves in such a way that when one valve opens the other valve closes, a lever mounted on the battery box and linked to said tie-rod, a spring holding the lever normally so as to close one of said valves and open the other, an adjusting screw at one 10 end of said lever, and a thermostatic device mounted upon a side of said battery box and coacting with one end of said lever.
- 15 2. The combination of a storage battery, a thermostat mounted adjacent said battery, and non-electric means operatively connected with said thermostat for varying the temperature of said battery.
- 20 3. The combination of a storage battery, a thermostat mounted adjacent said battery, and means operatively connected with said thermostat for varying the temperature of said battery, said means comprising a source 25 of gas under pressure, and means for directing said gas against said battery.
4. The combination of a storage battery, a thermostat mounted adjacent said battery, and means operatively connected with said 30 thermostat for varying the temperature of said battery; said means comprising a casing mounted adjacent said battery, and means for passing gas into said casing, said casing having apertures therein adjacent the 35 surface of said battery.
5. The combination of a storage battery, a thermostat mounted on said battery, a casing mounted adjacent said battery and having apertures therein, means for supplying 40 gas to said casing, and means comprising a valve operatively connecting said casing with said gas supplying means, and means operatively connecting said thermostat with said valve.
6. The combination of a battery, a thermostat and a casing each mounted adjacent said battery, said casing having apertures in the wall thereof, means for supplying warm gas, means for supplying relatively cool gas, means comprising a valve operatively connecting said casing with each of the respective gas supplying means, and means operatively connecting said thermostat with each of said valves. 45
7. The combination of a storage battery, a thermostatic device, a lever actuated by said device, a valve opened and closed by said lever, a casing partly surrounding said battery, and means for supplying gas through said valve and into said casing. 50
8. The combination of a storage battery, a thermostatic device, a lever actuated by said device, a valve opened and closed by said lever, a casing partly surrounding said battery, and means for supplying air through said valve and into said casing, said means comprising a funnel arranged to face forwardly. 55
9. The combination of a storage battery, a thermostat mounted adjacent said battery, and means operatively connected with said thermostat for varying the temperature of said battery; said means comprising a source of hot gas under pressure, a source of cool gas under pressure, and means for 60 directing either of said gases against said battery. 75

In testimony whereof, I hereunto set my hand.

CHARLES E. LINEBARGER.
